[57] CLAIM

The ornamental design for bumper tire for bowling ball return machine, as shown and described.

DESCRIPTION

FIG. 1 is a perspective view of a bumper tire for bowling ball return machine embodying my design;

FIG. 2 is a left side elevation of the tire shown in FIG. 1, the right side elevation, the top plan and the bottom plan being identical; and,

FIG. 3 is a front elevation, the rear elevation being a mirror image thereof.

FIG. 1

FIG. 3

FIG. 2
